UNITED STATES PATENT OFFICE.

BURHANS VAN STEENBERGH, OF GOSHEN, NEW YORK.

PROCESS OF MANUFACTURING GAS.

1,124,364.

Specification of Letters Patent.

Patented Jan. 12, 1915.

Application filed May 6, 1911. Serial No. 625,467.

To all whom it may concern:

Be it known that I, BURHANS VAN STEENBERGH, a citizen of the United States, residing at Goshen, in the county of Orange 5 and State of New York, have invented certain new and useful Improvements in Processes of Manufacturing Gas, of which the following is a specification.

This invention relates to a continuous 10 process of manufacturing gas suitable for illuminating, heating, and power purposes.

The object of my invention is, more particularly, to provide a continuous process 15 for generating gas by maintaining the exact temperature in the gas generator which experience has provided to produce from hydrocarbon oil, such as petroleum or its distillates, the largest possible percentage of high illuminants, such as hydrocarbon gases 20 of the athelene and ethene series— C_nH_{2n} ; C_nH_{2n-2} —without loss by destructive decomposition or by the formation of condensable tarry matter. The range of temperature through which these hydrocarbon 25 gases are produced and then decomposed with deposition of hard carbon and production of paraffin gases of low illuminating quality, is quite narrow, making it a matter of prime importance to keep the heat steadily and uniformly at the point just sufficient 30 to produce the above named high illuminants and just below the point or degree at which this same gas would be destructively decomposed and deposit hard 35 carbon, with the simultaneous production of inferior gas for lighting.

I have discovered by numerous experiments that the necessary exact regulation of the heat which will give the highest 40 grade or quality of illuminating gas, can be easily and economically maintained by a combination of the heat or combustion of carbon or other combustibles together with the heat produced by a proper resistance 45 material in an electric circuit of definite and uniformly maintained strength.

Another object of my invention is to provide for decomposing steam and hydrocarbon oil in properly regulating proportions 50 in contact with heated surfaces maintained at a constant temperature ranging between 1600° F. and 2000° F., and preferably about 1800° F., for rapidly producing a comparatively large volume of gas; and then car-

bureting or enriching such poor gas by 55 means of the rich hydrocarbon gases made in an upper heating zone of the generator by splitting up a suitable hydrocarbon oil into gas of the ethelene and ethene series at a temperature between 800° F. and 850° F. 60 suitable for the production of such gases without the deposition of hard carbon, lamp-black on the one hand or formation of tarry matter on the other hand. The temperature for generating gas of high illuminating 65 quality will range between 800° F. and 850° F., according to the gravity of hydrocarbon oil used.

The matter constituting my invention 70 herein will be defined in the claims.

I will now describe the construction of apparatus suitable for carrying out my process, by reference to the accompanying drawings, in which—

Figure 1 represents a vertical sectional 75 elevation of the generator, comprising the decomposing and fixing chambers and electric heaters. Fig. 2 represents a horizontal sectional view, taken on the line 2—2 of Fig. 1. Fig. 3 represents a perspective view of 80 one of the units or sections of the generator, a portion of said section being broken away to more clearly illustrate the construction. Fig. 4 represents a diagrammatic view, 85 illustrating the manner in which the electric heaters are connected up. Fig. 5 represents, on enlarged scale, a transverse section of an electric heater, such as shown in Fig. 1. Fig. 6 represents, on enlarged scale, a sectional view of an electric heater of modified 90 construction.

The apparatus comprises a series of alternate electric heating units—internally heated tubes—and fire-clay bars, superposed within non conducting walls, to form a continuous generator, and suitable electric connections, the electric heating units being employed to continuously maintain the exact degree of heat which will best effect the various chemical changes desired in the different zones of the generator.

The generator is composed of a plurality of superposed units, each unit carrying one or more electrical heaters and one or more tiles or intercepting members adapted to 105 present a very extended heating surface and cause the superheated steam and the vapors of the hydrocarbon oil to thoroughly com-

mingle and produce a fixed illuminating gas.

Referring now particularly to the drawings, the base of the generator, is denoted by 1, and the top or cover, by 2 which latter may be made of iron or of plate iron with a fire clay lining, between which parts are located a series of unit sections, Fig. 3, alike in form and construction. The base 1 is composed of a member, having a plate iron shell 3, a lining of asbestos 4, and an interior facing or lining 5 of fire-brick. An injector feed pipe 6 opens into this bottom section for supplying steam and oil or oil vapor. The steam will, preferably, be superheated and be thus used for injecting and atomizing a sufficient proportion of comparatively heavy hydrocarbon oil, the oil by the catalytic action of the superheated steam of the coatings on the electric heaters, being split into permanent gases, rich in high illuminants, such as gases of the olefine and perhaps acetylene series. By using electric heat the temperature can be so controlled between 800° F. and 850° F. as to split the hydrocarbon oils without decomposing the steam. The steam may also be commingled with the requisite proportion of oil vapor and the mixture pre-heated or superheated in a suitable chamber and then supplied in a regulated stream through pipe 6 to the base of the generator. Pipe 6 is provided with a controlling valve *a* for this purpose; and any suitable automatic regulating device may be used for introducing a continuous stream, at a uniform pressure, of steam and oil vapor into the base, or oil splitting or decomposing zone of the generator.

Each unit section preferably comprises a circular outer wall 7, made of plate iron and having an inwardly-projecting flange 8, said flange forming the support for the asbestos insulating lining 9 and the fire-brick lining 10, the outer edge of which terminates in substantial alinement with the inner edge of the inwardly-projecting flange 8. One or more tubes 11 (two being shown in the present instance) pass through the walls of the section and are clamped tightly in place by nuts 12, which bear against the washers 13, provided with concave faces adapted to fit the curvature of the shell or ring, 7.

Mounted in each tube is an electric heater, 55 which may be constructed in the following manner:—Finely-ground silica and finely-ground carbonate of lime are mixed with sodium silicate diluted with water and the pasty mass thus formed is wiped about or 60 molded around a relatively thin cardboard cylinder or tube 14, Fig. 5, and then allowed to harden. The outer coating is designated by 15. Mounted within the central portion of 65 the tubular member thus formed is a mass of granular carbon 16, and carbon elec-

trodes 16^a and 16^b are forced into the ends of the cardboard cylinder and tend to compress the particles of granular carbon to a greater or less extent and to thus establish a connection from end to end of the tube 70 between the electrodes. The electric heater thus produced is placed within the iron or other tube 11, and the outer coating, formed as above described, serves to insulate the heater from the iron tube and thus prevents 75 short-circuiting. To further insulate the heating member from the tube, suitable dielectric rings or washers 15^c are employed, being preferably located adjacent to the ends of the tube.

The cardboard will, when the current is passed through the heater, be burned away, becoming carbonized and forming in effect 80 a part of the electric conductor.

The iron tubes 11 will preferably extend 85 through the fire-brick walls of the unit sections and the cylinders 15 will be slipped through them.

Owing to the presence of the granular carbon extending longitudinally through the 90 center of the heaters, and in use of any desired number of tubes, the heat will be localized more or less in the plane of each unit section, across and through which the commingled steam and oil vapor must pass on 95 their way to the upper portion of the generator.

Located above the tubes or pipes 11 and 100 preferably extending at an angle thereto (in the construction shown, at right angles) is 105 a plurality of tiles or fire-brick bars 17 which become heated to approximately the same degree as the cylindrical heaters and serve by their extended heated surfaces to effect the splitting of the oil into hydrocarbon gases.

Another form of electric heater, consisting of a hollow tube 15^a, Fig. 6, five inches, more or less, in diameter, made of fire-clay, burned or baked at a temperature of about 110 3,000 degrees, the thickness of the tube to be not less than one inch, and the hollow filled 115 with granular carbon, and having carbon electrodes forced into the ends, may be used instead of the tubes 11—14—15 above described. The electrodes will compress the particles of carbon to a greater or less extent and thus establish a connection from 120 end to end of the tube.

The body of granular carbon compressed 125 between the ends of the electrodes 16^a and 16^b form a resistance, by means of which a succession of small or short electric arcs are produced, thus converting the electric energy into heat, thereby heating the tube at 125 that part filled with the granular carbon from the inside to the surface. The heat is localized within the fire-brick walls of the generator or unit sections due to the much greater resistance offered by the granular 130

carbon than that which is offered by the carbon electrodes, and such localized heat is imparted to adjacent tiles 17 and intervening space, so as to produce substantially uniformly heated surfaces and zones.

5 The iron tubes 11, extending through the generator, will be covered with a fire proof paste or wash 18, preferably composed of lime and magnesium moistened with a very dilute solution of sodium silicate for preventing the deposition of carbon on the iron. This coating also prevents iron, when heated to incandescence, from spoiling the illuminating quality of the gas by causing deposition of carbon; it also aids by catalytic action in splitting up the oil into gases of high illuminating quality. The fire-clay heater-tube, shown in Fig. 6, may also be coated with this protecting paste 18.

10 The commingled steam and oil vapor will pass uniformly around, and in contact with, the heated surfaces in their flow up through the decomposing zone of the generator. In case it is desired not to decompose the steam in the zones of the generator, a comparatively low temperature varying between 800° F. and 850° F., is maintained in the heaters, and the steam will carry the oil vapors in contact with the heated surfaces 15 where the oil vapors will be split up, so as to produce the greatest possible amount of high illuminants of the olefine series.

15 Each unit section will be provided with a plurality of lugs or ears 19 which register with similar lugs or ears formed upon the adjacent section or sections in order that the parts may be readily bolted together. Each section will likewise be provided with outwardly-projecting lugs 20 to which 20 chains and hooks or the like may be attached when it becomes necessary to elevate one or more of the sections for the purpose of withdrawing the section below and replacing it by a new section.

25 In assembling the sections they will be so placed that the heaters and tiles of one section will bear at right angles, or substantially so, in relation to the respective heaters and tiles in the sections above and below. 30 There is thus produced in the chamber of the generator numerous tortuous passages through which the gases must pass from the lower to the upper zone of the generator to the outlet pipe 21, located in the upper section, or, if preferred, in the cap or cover, as shown.

35 Any desired number of tile or fire-clay bars 17 may be arranged in checker-brick form between the electric heaters 14—16 to 40 provide the desired extent of heating surface and to insure that all the steam and oil vapor are brought into contact with numerous heated surfaces for effecting thorough and complete splitting of the oil into constituent gases, or decomposition and recom-

position of the elements, according to the temperature employed and the product desired.

45 The heaters of the alternate sections are connected to bus-bars 22, 23 and 24, 25, respectively, which bars are connected in circuit with a source of energy 26; and a switch 27 controls the circuits.

50 It will be readily understood that an automatic device, such as a thermostat, 28, 70 may be located at the outlet of each electric heater, or at suitable points in the wall of the generator to control the temperature by cutting out or cutting in the circuit according to the variations in the temperature. 75 Thus, the temperature may be kept within fixed limits and practically uniform, and so long as the proper quantity of oil vapor and superheated steam are supplied, the process will be a continuous one.

80 A transformer 29 is also, preferably connected with each set or pair of tubular heaters in a unit section for controlling the electro motive force, and consequently the temperature in each set of heaters. The 85 heat in the different zones of the generator will be regulated and controlled to the exact degree required for either splitting up the oil into its constituent gases of high illuminating power, or producing decomposition of the steam and oil when a large 90 volume of gas is desired.

95 Above the middle height from the base of the generator, about two-thirds of the height, I provide in the wall of the generator, two or more oil supply pipes 30, each having a valve *c* and a spray or atomizing nozzle *d* through which a suitable hydrocarbon is supplied to be split into illuminating gases at the appropriate temperature.

100 The process of making illuminating gas in this apparatus, may be conducted substantially as follows: By supplying or conducting the electric current to the heating tubes in the lowermost three or four of the 105 unit sections—about two-thirds of the height from the bottom—in a properly regulated voltage and amperage, the heating tubes, particularly the portions within the fire brick lining, containing the granulated carbon, will be heated to a temperature ranging between 1600° F. and 2000° F., and preferably between 1600° F. and 1800° F.

110 At the same time the electric current is conducted to the heating tubes of the two 115 uppermost unit sections having a voltage and amperage adapted to heat the granular carbon to a temperature ranging between 700° F. and 900° F., so as to heat the tubes and the adjacent fire-clay tiles to 120 about 800° F. or 850° F. Having suitably heated the lower and upper portions or zones of the generator to the respective temperatures above stated, a supply of superheated steam and preheated oil vapor, suit-

ably mingled, is admitted through pipe 6 into the base of the generator. Here a decomposition is effected by passage of the steam and oil vapor in contact with the heated surfaces at about 1800° F., causing decomposition of the steam by the oxygen thereof combining with carbon in the oil and setting the hydrogen of the steam free; also partially setting free the hydrogen of the hydro-carbon, but preferably producing a percentage of light carbureted hydrogen or marsh gas (CH₄). This marsh gas or methané will be retained in the gas at about a white heat, ranging between 1500° F. to 1600° F., and will pass on with the hydrogen and the carbon monoxid resulting from the decomposition of the steam. These highly heated gases pass upward above the decomposing zone and into the upper or carbureting zone of the generator, comprising two or more of the unit sections at the top of the generator. As soon as the gases above described are generated, a supply of suitable hydro-carbon oil or vapor is injected through the pipes 30 and discharged therefrom in an atomized condition centrally into the heated gasifying space of the generator. The resulting hydro-carbon vapor, will be immediately combined with and carried up by the hydrogen and light carbureted hydrogen into contact with the properly heated surfaces of the heating tubes and tiling in the two or more upper unit section of the generator, where a uniform heat is maintained of about 800° F., sufficient to produce complete gasification of all of the hydro-carbon introduced through pipes 30. The gasification here will be so complete and uniform that no carbon will be deposited and no volatile or unfixed vapor will be passed off. The fixed illuminating gas will be passed off from the outlet pipe 21 to the usual washer or any suitable cleaning apparatus. In continuing this process, the high heat of the lower zone or compartment of the generator is constantly maintained, resulting in the complete decomposition of the steam in reaction with the carbon, without deposit of lamp-black or hard carbon on the heating tubes or tiling. There will be no ash deposited.

In case it is desired to generate only high candle power illuminating gas, and not decompose steam, then all the electric heaters will be heated to a constantly maintained temperature of about 800° F. to 850° F., or at that degree which experience shows to be best for heating the steam so that it will exert its catalytic action in aiding to split the petroleum vapors into the largest possible percentage of high illuminant gases. The surfaces of the electric heater, composed of coatings of metallic oxids, such as 65 oxid of calcium and oxid of magnesium

mixed with dilute silicate of sodium, will be maintained at the best temperature for exerting the desired catalytic action to produce the largest possible percentage of high illuminants from the hydrocarbon oil used. 70 The hydrocarbon oil or vapor injected by jets of steam through pipes 6 and 30 will be split or resolved into gases, such as ethylene—C₂H₄; acetylene—C₂H₂; and methane—CH₄. The heat will never be carried 75 so high as to cause destructive decomposition of the oil vapors and a resulting deposit of part of the carbon in the form of lamp-black or hard carbon or decomposition of steam. Gasification of the hydrocarbon, 80 however will be complete, so that there will be little subsequent condensable matter in the gas after passing from the generator. This is practically, a continuous process for generating illuminating gas of uniform 85 quality or candle-power and without waste of hydrocarbons.

The paraffin hydrocarbons in by far the larger part of the various samples of American and Russian petroleum constitute 90 the principal, and sometimes almost the entire, substance, liquid and solid, of these oils and waxes. The gaseous paraffins in their illuminating quality are far inferior to the gaseous hydrocarbons of the olefine 95 series. By aid of properly regulated heat with auxiliary help of catalytics, such as steam and any one or several of the oxids of calcium, barium, strontium or magnesium in a heated state these paraffins in heated 100 vapors may be split chemically so as to produce large percentages of permanent gases of the olefine series and of the acetylene series, both of which are far more powerful 105 as illuminants than are the paraffin gases.

In the usual method of converting petroleum or its distillates into permanent gases for illuminating purposes there is more or less separation of solid carbon from the heated petroleum vapor with a correspondingly large production of paraffin gas of 110 low illuminating quality. The deteriorating and wasteful production of this low grade of gas I avoid by my above described process of making gas.

Having described my invention, what I claim, and desire to secure by Letters Patent, is—

1. The continuous process of manufacturing gas, which consists in continuously heating suitable contact material or surfaces to the required gasifying temperature, continuously supplying hydrocarbon oil or vapor in contact with said surfaces and constantly maintaining the temperature at substantially 120 the exact degree, between 800° and 850° F., for splitting or resolving the hydrocarbons into the largest possible percentage of permanent high illuminant gases of the olefine 125 series.

2. The process of manufacturing gas, which consists in continuously heating contact material and a catalytic agent material, to exert a catalytic action, to the required 50 gasifying temperature between 800° and 850° F., continuously supplying hydrocarbon oil or vapor in contact with the heated surfaces of said catalytic agents, and constantly maintaining the temperature at substantially the exact degree for resolving the 55 hydrocarbons into permanent gases of the olefine series having the largest possible percentage of high illuminants.
3. The process of manufacturing gas, which consists in continuously heating refractory material and a catalytic agent material to the required gasifying temperature between 800° and 850° F., continuously supplying and subjecting hydrocarbon oil or 60 vapor, together with a catalytic fluid, to contact with the heated surfaces of a catalytic contact material at a temperature between 800° and 850° F., and constantly maintaining the temperature at substantially 65 the exact degree for causing the hydrocarbons to be resolved in to permanent gases of the olefine series containing the largest possible percentage of high illuminants.
4. The process of manufacturing gas, which consists in continuously and uniformly heating by a controlled electric current, from within outward, a contact body and a catalytic agent material, to the required 70 gasifying temperature between 800° and 850° F., subjecting hydrocarbon oil or vapor to contact with the heated catalytic agent material and maintaining the said temperature by the interior electric current, at substantially the exact degree for causing the hydrocarbons to be resolved into permanent gases of the olefine series containing the largest possible percentage of high illuminants.
5. The process of manufacturing gas, 75 which consists in continuously heating a refracting body and a catalytic contact agent material to a high temperature required for decomposing steam, continuously supplying and subjecting steam and hydrocarbon oil or vapor to contact with said heated catalytic agent material, thereby causing mutual decomposition of the fluids, at the same time heating other bodies and their catalytic contact agent material to a lower temperature between 800° and 850° F., supplying hydrocarbon oil or vapor thereto while the temperature is maintained substantially at said 80 temperature for splitting or resolving the hydrocarbon into permanent gases of the olefine series containing the largest possible percentage of high illuminants, and mixing the gases first made from the decomposed steam with the high illuminant gases.
6. The process of manufacturing gas, 85 which consists in continuously heating by controlled electric currents refractory bodies and catalytic agent contact material to a relatively high heat, between 1600° F. and 2000° F. in one zone of a generator, and similar refractory bodies and material to a relatively low temperature in another or succeeding zone of the generator, continuously supplying hydrocarbon oil or vapor and steam to contact with said catalytic agent material in both zones of the generator, and maintaining the temperature of the refractory bodies and catalytic agent material in the second zone at substantially the required degree, between 800° and 850° F., for causing the hydrocarbons to be resolved into permanent gases of the olefine series containing the largest percentage of high illuminant gases.
